UNITED STATES PATENT OFFICE.

ROY T. AXE, OF SYRACUSE, NEW YORK, ASSIGNOR TO THE O. M. EDWARDS COMPANY INC., OF SYRACUSE, NEW YORK, A CORPORATION OF NEW YORK.

WINDOW SASH AND LOCK.

Application filed March 12, 1924. Serial No. 698,744.

This invention relates to window construction and has for its object a particularly simple and efficient arrangement and construction of a sash lock or holder on sashes having narrow stiles, particularly hollow sheet metal stiles.

The invention consists in the novel features and in the combinations and constructions set forth and claimed.

10 In describing this invention, reference is had to the accompanying drawings in which like characters designate corresponding parts in all the views.

15 Figure 1 is a fragmentary elevation of a corner of a sash embodying my invention, and the guide along which the sash moves being also shown.

20 Figure 2 is a transverse sectional view through one of the stiles of the sash, the contiguous portion of the guide or window stop being also shown.

25 Figure 3 is a transverse sectional view of the stile shown in Fig. 2, showing the form assumed thereby before the stile is fitted into the window guide, and the front and rear walls of the stile tensioned to press against opposing sides of the window guide.

30 Figure 4 is a view similar to Fig. 2 of another form of stile construction in which the front and rear walls of the stile are tensioned in a reverse manner from that shown in Fig. 2.

35 Figure 5 is a view similar to that of Fig. 3 of the construction shown in Fig. 4.

40 Figure 6 is an edge view looking downwardly on the sash lock, the contiguous portion of the stile being also shown in broken lines.

Figure 7 is an elevation of the detached lock.

45 Figure 8 is a fragmentary view of the window guide showing the stop openings therein.

50 1 designates one of the stiles, and 2 the lower rail of the sash joined together at the corner of the sash in any suitable manner and each being usually formed up out of sheet metal. In Figs. 2 and 3, the stile is shown as consisting of resilient sheet metal bent in the general form of a U-shaped channel open at its outer edge and the front and rear walls 3, 4 being flared outwardly and spaced apart a greater distance than the width of the window guide 5, which is shaped to form a channel 6 in which the

window sash slides, the front and rear walls 3, 4 being compressible toward each other from the position shown in Fig. 3 in order to be placed in the channel 6 of the guide 5, and, when so located in the channel 6, to be tensioned to press outwardly against the walls of the channel and thus tighten the sash in the channel to prevent rattling, and also to serve as weather stripping.

55 Each stile 1 and also the rail, as 2, are also bent to form an inwardly facing channel 7 to receive the margin of the pane of glass or to receive other means for holding and cushioning the pane of glass in the channel 7.

60 Preferably a filler block 8, as of wood, is arranged between the front and rear walls 3, 4, this filler block resting against the bottom wall of the channel 7 and extending to or beyond the outer edges of the walls 3, 4. The block is also formed with clearance spaces 9 on its front and rear sides for permitting the tensioning of the resilient walls 3, 4 by being pressed toward each other against their inherent resiliency. The filler block can be readily trimmed off at its edges to fit the window sash to the window frame. The block is secured to the bottom wall of the channel as by screws 8a.

65 In Figs. 4 and 5, the front and rear walls 11, 12 of the stile 10 are normally spaced apart a less distance than the width of the window guide 13, which projects between such walls 11, 12, the walls 11, 12 being movable outwardly away from each other to tension the same and to engage, when tensioned, the outer faces of the guide 13 and press toward each other against such faces and hence act to tighten the sash and as a weather stripping. In the form shown in Fig. 5, the clearance spaces 14 are formed between the filler blocks 15 and the front and rear walls 11, 12 and the front and rear walls 11, 12 extend laterally beyond the edge face of the filler block 15 to form a channel for receiving the guide 13.

70 16 designates a sash lock which includes a base plate 17 suitably secured to the sash, preferably at the corner thereof, and 18 is a lock lever pivoted at 19 to the base 17 and having an angularly extending pinch handle 20 arranged in juxtaposition to a handle 21 fixed to the base plate 17, in the usual manner. The lock lever 17 is provided with an arm 22 overlying the sash and extending 75

lengthwise of the stile and having an inwardly and angularly extending arm 23 projecting through an opening 24 in one of the walls, as the wall 12 of the stile, this arm 22 having means within the stile for coacting with the window guide, this means being here shown as a nose or lock bolt 25 extending laterally from its inner end and arranged to engage any one of the number of 10 holes 26 in the guide 13 to lock the sash in closed position or at different elevations. The lock 18 is pressed toward its closed position by a suitable spring 27. The filler block 15 if used is also provided with a 15 suitable recess 28, in which the angularly extending arm 23 and its nose 25 is located.

This window sash and lock construction is particularly adapted for railway cars and motor vehicles or busses, particularly motor 20 vehicles where the stiles and rails are necessarily narrow and as light as possible, and, owing to its construction, can be manufactured economically and sold at such a low price as to be commercial for motor busses.

25 What I claim is:

1. In a window sash construction, the combination with a window guide, of a sash movable along the guide and including a hollow sheet metal stile open at its edge, one 30 wall of the stile being formed with a slot therethrough above the level of the rail of the sash and a sash lock comprising a base mounted on the outer side of the sash at the corner thereof and mechanism including a 35 movable element carried by the base and extending lengthwise of the stile on the outer side thereof having an arm extending through the slot into the stile and means at the inner end of said arm within the sash for coacting with the guide, said means and guide coacting through the open edge of the stile.

2. In a window sash construction, the combination with a window guide and a sash 45 movable along the guide and formed with a stile having a hollow portion opening through the edge of the sash and with a slot extending through one of the walls of the hollow portion above the level of the 50 rail of the sash, a sash lock comprising a base on the outer side of the sash and mechanism carried by the base including a lever pivoted to the base and having an arm extending lengthwise of the stile and provided 55 with an angular arm extending through the slot into the hollow portion of the stile and means at the inner end of said arm within the stile for coacting with the guide.

3. In a window sash construction, the combination of a window guide in the form of a rib, a sash movable along the guide and having a stile formed with the hollow portion coacting with the guide, one wall of the hollow portion of the stile being formed 65 with a slot, the rib extending into the hol-

low portion, a sash lock comprising a base mounted on the outer side of such wall of the hollow portion and a lever supported by the base and having an arm extending upwardly lengthwise of the stile on the outer side thereof, said arm having a lateral extension at its upper end extending through the slot into the hollow portion of the stile, and means within the stile at the inner end of the lateral extension for coacting with the rib.

4. In a window sash construction, the combination with a window guide of a sash having a hollow sheet metal stile U-shaped in general form in cross section, one of the walls of the U-shaped formation being formed with a slot therethrough above the level of the lower rail of the sash and a sash lock comprising a member extending lengthwise of the stile on the outer side thereof and having an angular arm extending through the slot to the inside of the stile and means within the stile at the inner end of said arm for engaging the guide, said member having a handle on the outside of the sash.

5. A window sash construction comprising a hollow, sheet metal member open at its edge, the guide having a portion extending into the sash member through the open edge thereof, one wall of said member being formed with an opening therethrough and a sash lock comprising a base mounted on the outer side of the sash member, and a movable locking lever carried by the base and mounted to move about an axis at an angle to the plane of said sash member, and having an angular portion extending through said slot, and a window guide extending into the sash member through the open edge thereof, the angular portion of the locking lever coacting with the guide.

6. A window sash construction comprising a hollow, sheet metal stile in the form of a channel open at its edge, a guide having a portion extending into the stile through the open edge thereof, one wall of said stile being formed with an opening therethrough and a sash lock comprising a base mounted on the outer side of the stile, the lever having an arm extending upwardly lengthwise of the stile on the outside thereof, and a movable locking lever carried by the base and mounted to move about an axis at an angle to the plane of said sash member, and having an angular portion extending through said slot, and the window guide extending into the sash member through the open edge thereof, the angular portion of the locking lever coacting with said guide, the guide being formed with openings in its inner edge opposed to the bottom of the channel, and the angular portion of the lever being arranged to enter said openings.

7. In a window sash construction, a sash member comprising a stile formed with a hollow portion opening through the edge of the stile and with a slot extending through one of the walls of the hollow portion, said slot being located above the level of the lower rail of the sash, a sash lock comprising a base mounted on the outer side of the hollow portion and mechanism comprising a lever mounted on an axis at an angle to the plane of the sash, the lever having an angular portion extending through the slot and having an engaging head at its inner end within the hollow portion whereby the lever moves toward and from the open edge of said hollow portion, and a guide for the sash having means with which the engaging end of the lever coacts.

8. In a window sash construction, a stile formed with a hollow portion opening through the edge of the sash and with a slot opening through one of the walls of the hollow portion, the slot being located in the stile above the level of the lower rail of the sash, a sash lock comprising a base mounted on the stile and mechanism including a movable lever pivoted to the base and movable transversely of the stile, the lever having a portion extending through the slot and provided with an engaging head at its

inner end within the hollow portion of the stile whereby the lever moves toward and from the open edge of said hollow portion and a guide for the sash having means with which the engaging end of the lever coacts. 35

9. In a window sash construction, a stile formed with a hollow portion opening through the edge of the sash and with a slot opening through one of the walls of the hollow portion, the slot being located in the stile above the level of the lower rail of the sash, a sash lock comprising a base mounted on the stile and mechanism including a movable lever pivoted to the base and movable transversely of the stile, the lever having a portion extending through the slot and provided with an engaging head at its inner end within the hollow portion of the stile whereby the lever moves toward and from the open edge of said hollow portion 40 and a guide for the sash having means with which the engaging end of the lever coacts, 45 said guide extending into the hollow portion.

In testimony whereof, I have hereunto signed my name, at Syracuse, in the county of Onondaga, and State of New York, this 6th day of March 1924. 50

ROY T. AXE.
